UNITED STATES PATENT OFFICE.

JOSEPH L. HART, OF CHICKASHA, OKLAHOMA.

DOUBLE-BREASTED-HULLER COTTON-GIN.

982,672.

Specification of Letters Patent. Patented Jan. 24, 1911.

Application filed September 23, 1909. Serial No. 519,127.

To all whom it may concern:

Be it known that I, JOSEPH L. HART, a citizen of the United States, and a resident of Chickasha, in the county of Grady and State of Oklahoma, have invented certain new and useful Improvements in Double-Breasted-Huller Cotton-Gins, of which the following is a specification.

My invention relates to improvements in devices for hulling and ginning cotton and it consists in the constructions, combinations and arrangements herein described and claimed.

The present invention is somewhat similar to that disclosed in my prior application Serial No. 510,617, filed July 21, 1909. In place, however, of suspending the ribs from one end as in said prior application I make use of a double set of ribs which are secured 20 at both ends.

An object of my invention is to provide a device having a series of transverse rods to which the gin ribs may be attached and from which any one of a number of ribs can 25 be conveniently removed without disturbing the other ribs in the row.

A further object of my invention is to provide a device by which the individual gin ribs may be attached or detached without 30 necessitating the use of screws, bolts or other fastening devices.

Other objects and advantages will appear in the following specification and the novel features of the device will be particularly 35 pointed out in the appended claims.

My invention is illustrated in the accompanying drawings, in which—

Figure 1 shows a section through the device, and Fig. 2 is a front view of the device 40 a portion of the outside casing being broken away.

In carrying out my invention I provide a casing which forms the front of the huller breast. At the top of the casing is an opening B into which the cotton is fed. A semi-circular member C forms the back part of the huller breast. Below the member C is a rod D which runs through the device from end to end whose purpose will be explained 45 later. At the bottom of the casing is mounted a picker-roll F provided with rows of small teeth or spikes f. The picker-roll is mounted on a shaft G and may be rotated by any suitable mechanism. Behind 50 the picker-roll F are two rods H and K

which run through the device from end to end in the same manner as the rod D.

At the rear of the device is a rail or supporting member L below which is another rod M similar to the rods D, H and K, before mentioned. The roll-box is shown at R. The back of this box is formed by the rail L. At each end of the roll-box is a revolving head X which is supported on the shaft x carried by the hanger Y.

The saws S are mounted for revolution on a shaft s, and are sufficient in number to correspond with the size of the device. Below the saws is an inclined member E for the reception of the seeds.

In order to give the cotton the right pitch toward the saws S, I provide a hinged board P. This board may be tilted around its pivotal support and kept in its tilted position by any suitable means so as to extend at an angle to the front part of the huller-breast as shown in Fig. 1. At the bottom of the huller-breast in the front side thereof is a similar adjustable board Q for regulating the discharge of the hulls. At U, I have shown a rod provided with arms u which project between the saws, as shown in Fig. 1, and which may be adjusted away from or toward the roll in the roll-box R so as to permit the regulation of the action of the 85 saws upon the cotton.

The parts thus far described with a few exceptions are similar to those shown in the prior application No. 510,617. The main point of novelty as stated before lies in the 90 gin ribs themselves. These ribs are shown in Fig. 1 at V and W. The ribs V are provided at their upper ends with the rearward facing slots v arranged to receive the rod D. Each rib is provided with a flanged portion v' adapted to abut a similar flanged portion of the adjacent rib. The rib V is bent inwardly past the edge of the saws S, then around in a curve concentric with the curve of the saw. The rib begins to turn and flatten at a point v² and is provided at its lower end with a forwardly facing slot v³. The bottom part of the rib is provided with a flange v⁴ similar to the flange v' at the top. 100

The rear set of ribs W are each provided with the rearwardly facing slots w and the forwardly facing slots w³ similar to the slots v and v³ and with the flanges w' and w⁴. Each rib has also an upwardly extending portion w⁵ adapted to abut against the 110

rail L. The ribs are bent forwardly around the shaft s and then rearwardly, being flattened at the portion w² as shown in Fig. 1.

From the foregoing description of the various parts of the device the operation thereof may be readily understood.

In assembling the device, the ribs V and W are slipped over the rods D—H and M—K with their respective upper and lower flanges abutting the adjacent ribs. Each of these rods is threaded at both ends and is provided with nuts N and N', as shown in Fig. 2. The nuts N and N' are tightened, firmly clamping the ribs against the end Z of the casing, see Fig. 2. The extension w³ tends to steady the rib and insures the alignment of the set.

The cotton passes down through the opening B and is caught by the saws and drawn into the roll-box, the seeds pass down between the front and rear ribs V and W, respectively, and drop upon the inclined plane E thus discharging the seeds at a point beneath the saw or under the gin instead of in front of it in the ordinary way.

I claim:

1. In a combined huller and gin, a frame, a series of rods running longitudinally of said frame, a series of gin ribs, each rib being provided with upper and lower slots arranged to straddle certain of said rods, means

for spacing said gin ribs apart and means for clamping said ribs simultaneously.

2. In a combined huller and gin, a frame, an upper and a lower rod running longitudinally of said frame, a series of gin ribs each provided with an upper slot and a lower slot adapted to straddle the respective rods, upper and lower spacing flanges carried by each gin rib adapted to abut similar spacing flanges on adjacent ribs and means for clamping said ribs simultaneously.

3. In a combined huller and gin, a frame provided with end members, a rear rail extending longitudinally of said frame, an upper and a lower rod extending longitudinally of said frame, a series of ribs, each rib having upper and lower slots arranged to straddle the respective rods, spacing flanges carried upon said ribs immediately adjacent the slots, said flanges being arranged to abut similar flanges on adjacent ribs, an upwardly extending flange at the top part of the rib arranged to abut against said rail when the ribs are in their normal positions upon the rods, and nuts on said rods for clamping the ribs between said end members.

JOSEPH L. HART.
